GAME BOARD

Edward T. McNaney, 101 S. Hilltop Road,
Catonsville, Md.

Filed May 16, 1962, Ser. No. 70,163

Term of patent 14 years

(Cl. D34—5)

The single FIGURE is a plan view of a game board showing my new design.

The game board shown in the drawing is of conventional thickness.

I claim:

The ornamental design for a game board, as shown and described.
